US0D1114022S

(12) **United States Design Patent** (10) **Patent No.:** **US D1,114,022 S**
(45) **Date of Patent:** **** Feb. 17, 2026**

(54) **MONITORING CAMERA**

(71) Applicant: **AGC Inc.**, Tokyo (JP)

(72) Inventors: **Kazuki Isono**, Ayase (JP); **Mayu Ogawa**, Tokyo (JP); **Yuichi Yamada**, Tokyo (JP)

(73) Assignee: **AGC Inc.**, Tokyo (JP)

(**) Term: **15 Years**

(21) Appl. No.: **35/522,764**

(22) Filed: **Oct. 20, 2023**

(80) **Hague Agreement Data**

Int. Filing Date: **Oct. 20, 2023**

Int. Reg. No.: **DM/233992**

Int. Reg. Date: **Oct. 20, 2023**

(57) **CLAIM**

The ornamental design for a monitoring camera as shown and described.

DESCRIPTION

3. Monitoring camera

3.1 : Perspective view 1

3.2: Perspective view 2

3.3: Front

3.4: Rear view

3.5: Top

3.6: Bottom

3.7: Right-side view

3.8: Left-side view

3.9 : Cross sectional view taken along line A-A

Protection is claimed for the portions except the portions illustrated with dashed lines; the dashed lines form no part of the claimed design; the dash-dotted line indicates the boundary between the portion for which a design registration is sought and other portions; the extension lines and label A in reproduction 3.3 are for reference purposes only and form no part of the claimed design.
